[57] CLAIM

The ornamental design for a merchandise display stand
or similar article, as shown and described.

DESCRIPTION

FIG. 1 is a front perspective view of a merchandise
display stand or similar article showing my new design;
FIG. 2 is a rear perspective view thereof; and
FIG. 3 is a top view thereof.

The invention being characterized in that the principal
header extends the length of the display and the subsidiary
headers extend outwardly at an angle from the
principle header and are curved at their base to give the
appearance of merging into the principle header as best
shown in FIG. 3.
